UNITED STATES PATENT OFFICE

GEORGE A. COMBRIDGE, OF LOS ANGELES, CALIFORNIA

INDICATOR

Application filed September 10, 1930. Serial No. 480,875.

This invention is an indicator adapted for use in a public conveyance such as a street car traveling a predetermined route, and has for its object to successively display for the information of passengers the names of the various stops along the route. 5

More particularly it is the object of the invention to provide the names of the various stops on a movable sign element, and to shift 10 the sign element step-by-step as the successive stops are approached, in order that the passengers may be advised as to the next stop of the vehicle.

It is a further object of the invention to 15 provide simplified means for moving the sign element step-by-step, and to provide a remote control for the actuating mechanism, with said remote control readily accessible to the operator of the vehicle.

It is a still further object of the invention to 20 initiate movement of the sign element by manual operation of the remote control, and to automatically stop said movement of the sign element when it has been shifted sufficiently to display the name of the next succeeding stop, thereby insuring the desired 25 step-by-step movement of the display mechanism without requiring accurate manual control by the operator.

Further objects of the invention will be 30 readily understood from the following description of the accompanying drawing which illustrates the mechanism in somewhat dia- grammatic form, and in which:

Fig. 1 is a transverse section through a 35 public conveyance such as a street car and illustrating one practical embodiment of the invention.

Figs. 2, 3 and 4 are detail sections on the 40 lines 2-2, 3-3 and 4-4 respectively of Fig. 1.

Fig. 5 is a detail section through the man- 45 ual control for the mechanism.

The invention is illustrated as embodied in 50 a public conveyance such as a street car A,

and may comprise a casing 1 having a sight opening 2 for successively displaying the names of the stops along the route of the car, the names of the stops being provided at 3 on a tape 4 which is adapted for step-by-step movement past the sight opening, with the casing 1 so mounted in car A that the sight opening is conveniently visible to the passengers.

The tape 4 may be wound on rollers 5, and 55 is preferably shifted for successively displaying the names 3 at the sight opening 2, by means of sprockets 6 which are mounted on a shaft 7 and which are adapted to engage notched edges 8 of the tape, it being understood that the roller 5 which is winding up the tape as it is unwound from the other roller, is adapted to be driven by any usual driving connection (not shown), such as ordinarily employed in this art. The shaft 7 is pref- 60 erably rotated by a drive mechanism which is started by a manual control, and after predetermined rotation of the shaft such as is just sufficient to move the tape 4 so as to display the next succeeding name 3, the 65 drive mechanism is preferably automatically stopped so as to insure just the desired step-by-step movement of the sign element.

As an instance of this arrangement the shaft 7 may be driven by an electric motor 10, 75 preferably through suitable gearing 11-12, and an electric circuit 13 for the motor may be closed by a manually operated switch 14 which is positioned convenient to the operator of the conveyance in which the indicator is installed. Closing the switch 14 thus initiates rotation of shaft 7, and an auxiliary switch 15 then automatically closes a shunt circuit 13a for the motor, and at the same 80 time the switch 14 is automatically opened so that rotation of shaft 7 is continued under control of the switch 15, and this switch is automatically opened after such predetermined rotation of the shaft as will shift the 85 90

tape 4 so as to aline the next succeeding name 3 with the sight opening 2.

As shown at Fig. 5 the switch 14 may comprise a pivoted lever 16 and a spring-projected pin 17 carrying cooperating contacts 18-19, with the proximate ends of the lever and pin tapered as shown at 20-21 so that when the lever is swung in either direction the engagement of tapered ends 20-21 insures continued movement of the lever beyond dead center and to one or the other of the positions shown in full and broken lines in Fig. 5. As the lever moves past dead center the contacts 18-19 thus momentarily engage and then immediately disengage, and consequently manual operation of switch 14 is adapted to make and then immediately break the circuit 13, without requiring careful manipulation on the part of the operator and simply by flipping the lever 16 to one or the other of the positions shown in Fig. 5.

As shown in Fig. 3 the auxiliary switch 15 may comprise a contact 22 and a disc 23 fixed on shaft 7 with a pair of arcuate contact strips 24 on the periphery of the disc and spaced apart at diametrically opposite insulated points 25, so that with the disc turned for alinement of either of the insulated points 25 with contact 22 the shunt circuit 13a is opened, and rotation of disc 23 will engage contact 22 with one or the other of strips 24 and thus close circuit 13a for supplying electrical energy to motor 10 until the disc has been so turned as to aline the other insulated point 25 with the contact 22, upon the shunt circuit is automatically opened and the motive power is cut-off.

Means are preferably provided for positively stopping rotation of disc 23 immediately upon breaking the motor circuit 13a so as to insure exact alinement of contact 22 with one or the other of the insulated points 25, and for this purpose and as shown in Fig. 4 a disc 26 may be fixed on shaft 7, with one or the other of diametrically opposite recesses 27 in the periphery of the disc adapted for engagement by a locking pin 28 when the mechanism is at rest. The pin 28 is retracted when the motor 10 is started, thereby releasing the disc 26 for rotation of shaft 7, and as soon as the disengaged recess 27 is clear of pin 28 the pin is spring-projected so as to ride on the periphery of disc 26 and thus drop into the diametrically opposite recess 27 for immediately stopping rotation of shaft 7 when the motor circuit 13a is subsequently broken. The pin 28 may be retracted by an electro-magnet 29 in circuit 13, the magnet being energized by closing switch 14 and thus retracting pin 28, and the magnet being then immediately de-energized as a result of the previously described breaking of contact at switch 14 so that the pin 28 is again spring-projected ready for its locking engagement.

With the mechanism in the position shown

in the drawing the switches 14 and 15 are open, thereby breaking circuits 13 and 13a so that motor 10 is at rest with one of the names 3 of tape 4 displayed at sight opening 2 and the shaft 7 locked against turning by pin 28. 70 When the conveyance has moved beyond the indicated stop and it is desired to advise the passengers as to the next stop along the route, the operator flips the switch lever 16 from its full to its broken line position as shown 75 in Fig. 5, thereby closing the circuit 13 which however is broken momentarily thereafter by the engagement of the tapered end surfaces of lever 16 and pin 17. The momentary closing of circuit 13 energizes electro-magnet 29 80 for retracting pin 28 and also starts rotation of shaft 7 by the motor 10. Since disc 23 turns with shaft 7, one or the other of strips 24 will thus engage contact 22 so as to close the circuit 13a and thus continue the supply 85 of electrical energy to motor 10 after circuit 13 is opened, and the rotation of shaft 7 is thus continued until the motor is stopped by the contact 22 alining with the diametrically opposite insulated point 25, whereupon 90 the pin 28 is spring-projected into engagement with the alined recess 27 for stopping the shaft 7 with the parts in their normal position of rest, with the predetermined rotation of shaft 7 which is thus obtained having 95 shifted the tape 4 just a sufficient distance to aline the next succeeding name 3 with the sight opening 2. The operation may then be repeated to display the next succeeding name of tape 4, by simply flipping switch lever 16 100 in the opposite direction.

The mechanism may be adapted for reversal when the end of the route is reached, so as to successively display the names 3 in the reverse order as the route of travel is retraced, it being simply necessary to reverse the direction of rotation of shaft 7, which may be accomplished in any well known manner, as for example by employing a motor 10 of a type which is adapted for reversal 110 at the will of the operator.

The invention thus provides for step-by-step movement of an indicator carrying predetermined signs adapted for successive display at a sight opening, with movement of the indicator initiated by operating a manual control but automatically stopped when a predetermined shift has been obtained, so as to insure exactly the desired step-by-step movement irrespective of careless handling 115 of the manual control and without requiring skillful manipulation thereof for stopping the mechanism at the end of the predetermined movement.

I claim:

1. In combination a shiftable sign element, an electric motor for shifting the sign element, a main switch for starting the motor, said switch being adapted for continuing movement in the same direction after 130

the switch is closed, with said continuing movement opening the switch momentarily after its closing, an auxiliary switch controlling the motor and adapted to be closed by initial rotation of the motor so as to continue rotation of the motor after the main switch is opened, and means for opening the auxiliary switch for stopping the motor after predetermined shifting of the sign element.

2. In combination a shiftable sign element, an electric motor for shifting the sign element, a main switch for starting the motor, said switch being adapted for continuing movement in the same direction after the switch is closed, with said continuing movement opening the switch momentarily after its closing, an auxiliary switch controlling the motor and adapted to be closed by initial rotation of the motor so as to continue rotation of the motor after the main switch is opened, means for opening the auxiliary switch for stopping the motor after predetermined shifting of the sign element, and means for releasably securing the sign element against shifting when the motor is stopped.

3. In combination a shiftable sign element, an electric motor for shifting the sign element, a main switch for starting the motor, said switch being adapted for continuing movement in the same direction after the switch is closed, with said continuing movement opening the switch momentarily after its closing, an auxiliary switch controlling the motor and adapted to be closed by initial rotation of the motor so as to continue rotation of the motor after the main switch is opened, means for opening the auxiliary switch for stopping the motor after predetermined shifting of the sign element, means for automatically securing the sign element against shifting when the motor is stopped, and a solenoid energized by the momentary closing of the main switch for releasing the securing means.

4. In combination, a sign element, a rotatable shaft adapted to shift the sign element, an electric motor for the shaft, a main switch for starting the motor, said switch being adapted for continuing movement in the same direction after the switch is closed, with said continuing movement opening the switch momentarily after its closing, an auxiliary switch controlling the motor, said auxiliary switch comprising an element fixed on the shaft and a cooperating stationary contact, the initial rotation of said element with the shaft being adapted to close the auxiliary switch for continuing rotation of the shaft after the main switch is opened, and the continued rotation of said element with the shaft being adapted to open the auxiliary switch after predetermined shifting of the sign element, means for locking the shaft against rotation, and a solenoid energized by closing the main switch, the solenoid when energized releasing the locking means.

5. Control mechanism for a sign element which is adapted for shifting by an electric motor having an auxiliary switch closed by initial rotation of the motor and opened after predetermined rotation thereof; the control mechanism comprising a switch adapted to be closed for starting the motor and adapted for continuing movement in the same direction after being closed, with said continuing movement opening the switch momentarily after its closing.

In testimony whereof I have affixed my signature.
